(57) CLAIM

The ornamental design for a digital camera, as shown and described.

DESCRIPTION

FIG. 1 is a top, front and right side perspective view of a digital camera showing my new design;

FIG. 2 is a bottom, rear and left side perspective view thereof;

FIG. 3 is a front view thereof;

FIG. 4 is a rear view thereof;

FIG. 5 is top plan view thereof;

FIG. 6 is a bottom plan view thereof;

FIG. 7 is a right side view thereof;

FIG. 8 is a left side view thereof;

FIG. 9 an alternate front perspective view showing the camera in use; and,

FIG. 10 is an alternate rear perspective showing the camera in use, the broken line showing of a fragmentary human hand is for illustrative purposes only and forms no part of the claimed design.

FIG. 11 is a perspective view showing the second embodiment of a digital camera, as seen obliquely from the front right upper side thereof, in which the portion except thinly smeared with India ink is the one for which a right as design invention is sought; and,

FIG. 12 is a perspective view, as seen obliquely from the rear right lower side thereof, in which the portion except thinly smeared with India ink is the one for which the right as design invention is sought.
